[57] CLAIM

The ornamental design for a golf cart handle, as shown and described.

DESCRIPTION

FIG. 1 is a top view of a golf cart handle illustrating my new design;

FIG. 2 is a bottom view thereof showing extra golf ball holders each side of the shaft position;

FIG. 3 is a side view thereof, the opposite side being a mirror image thereof, and is shown with the score card cover opened and with an attachable cup holder;

FIG. 4 is an end view thereof, shown with the attachable cup holder; and,

FIG. 5 is a perspective view of the golf cart holder illustrating the bottom thereof.

FIG. 1

FIG. 3
